UNITED STATES PATENT OFFICE.

VICTOR MARENDSKSI, OF PARIS, FRANCE.

STUD FOR SPRING-PRESSURE FASTENERS OR BUTTONS.

1,380,000.

Specification of Letters Patent. Patented May 31, 1921.

Application filed September 12, 1917. Serial No. 190,933.

To all whom it may concern:

Be it known that I, VICTOR MARENDSKSI, mechanical engineer and patent agent, of 34 Boulevard Voltaire, at Paris, Department of the Seine, France, citizen of Poland, have invented certain new and useful Improvements in Studs for Spring-Pressure Fasteners or Buttons; and I do hereby declare the following to be a full, clear, and 10 exact description of the invention, such as will enable others skilled in the art to which it appertains to make and use the same.

The invention relates to a new form of stud heads for pressure buttons. There are 15 already known studs which are formed by the folding or by the stamping of a metal strip to be introduced by pressure in the socket.

The invention consists to give to the elongated head of the stud button a shape of an M with rounded parts for the purpose of increasing, by the multiplicity of the flexible points, the working of the stud's spring.

In the drawing, the Figure 1 shows, in 20 elevation, a form of execution and the Figs. 25 2 and 3 show, in elevation and in plan, a

modification of the improved head of the stud.

The elongated heads of the studs having two lateral legs 4 connected to the basis 1, 30 instead of being simply open or closed at the top, are curved once or twice in the middle as in 2 and 3 so as to present the shape of an M.

By that shape of execution of the head 35 the number of the elastic points is larger so that the head works better and has a better elasticity.

I claim:

A stud for spring pressure buttons or fasteners having elongated heads composed of two lateral legs connected to the basis and curved in the middle in the form of an M with rounded parts for the purpose of increasing, by the multiplicity of the points 40 45 of flexibility, the working of the stud's spring, substantially as described, illustrated and set forth.
